UNITED STATES PATENT OFFICE.

FRANK WILSON, OF BATON ROUGE, LOUISIANA.

REVERSING MECHANISM FOR WASHING MACHINES.

Application filed March 6, 1928. Serial No. 259,513.

This invention relates to washing machines, and particularly to certain improvements in the gearing shown in my Patent #1,468,588, granted on September 18, 1923.

5 The patent above referred to illustrates a washing machine wherein there is an outer tank, an inner cylindrical clothes holder disposed within the tank, the tank being filled or partially filled with water, and the 10 clothes holder being mounted to rotate continuously in one direction so long as the power is applied thereto unless reversed by hand.

The general object of the present invention is to provide an improvement upon this construction by providing automatic means for securing an intermittent reversal of the movement of the drum or clothes holder.

Other and more specific objects will appear in the course of the following description.

My invention is illustrated in the accompanying drawings, wherein:—

Figure 1 is a side elevation of a washing machine with gearing embodying the improvements of the present invention;

Figure 2 is a transverse sectional view on the line 2—2 of Figure 1;

Figure 3 is a vertical longitudinal section 36 of the machine;

Figure 4 is a side elevation of the gearing, as it would appear looking from the inside of the machine with the parts in neutral position;

Figure 5 is a similar but fragmentary view showing the parts in one of the operating positions;

Figure 6 is a detail sectional view on the line 6—6 of Figure 4;

Figure 7 is a detail view of a locking device employed.

Referring to the drawings, it will be seen that the washing machine comprises an outer tank constructed in two sections, the lower section being designated 10 and the upper section 11. The upper section is operatively hinged to the lower section so that it may be turned up and this tank may be of any suitable form and the cover or lid 50 section of the tank is preferably semi-cylindrical in form. The tank is provided at its upper end with means 12 whereby it may be filled with water to any desired height and the latching means 13 whereby the two 55 sections may be held closed. This outer

tank is supported upon a frame, designated generally 14, including vertically extending legs.

Disposed within the outer tank is an oscillatable cylindrical drum 15 which is preferably informed in two sections, the sections being hinged to each other at 16 and provided with latching means at the opposite end. The perimeter of this drum 15 is perforated, as at 17, and the side walls of the drum are also perforated, as at 17. The drum also is provided with inwardly extending flanges or paddles 18 which act to support the clothes within the drum and cause the clothes to move around with the drum. So far, the construction is such as described in my patent above referred to.

The drum is mounted upon trunnions 19 and 20, the trunnion 20 being in the form of a shaft supported in suitable bearings in the frame and extending out therefrom and supporting upon it the gear wheel 21. This gear wheel 21 meshes with two pinions 22 and 23 also mounted upon the frame in the manner shown in Figure 4, and the gear wheel 21 adjacent its center is provided with the beveled gear teeth 24. Mounted upon a transversely extending frame bar 25 which forms part of the frame supporting the gearing is a transversely extending shaft 26 having a beveled pinion 27 at its inner end meshing with the beveled gear teeth 24. The opposite end of this shaft is provided with a pinion 28 which extends through the slot in the cross bar 25 and engages the teeth on a rotatable nut 29 whose function will be later described.

For the purpose of driving the gear wheel 21, I provide a driving shaft 30 which is supported in any suitable manner upon the frame of the machine and is connected to a motor M in any suitable way, this driving shaft carrying upon it a pinion 31. Oscillatably mounted upon the driving shaft as upon a center is a lever 32 which carries upon it a gear wheel 33 which meshes with the pinion 31 at all times and which also meshes with a pinion 34 also mounted upon the lever to one side of the middle thereof.

Disposed in engagement with the pinion 22 is a gear wheel 35 and meshing with the pinion 23 is a gear wheel 36. Each of these gear wheels has a relatively large radius in comparison with the radius of the pinions 23. These gear wheels 35 and 36 are mount-

- ed in suitable bearings upon the vertical supporting bars 37 of the gear supporting frame, which supporting bars engage with and support the transverse bar 25. By 5 shifting the lever 32 to the right hand side in Figure 4, the gear wheel 33 will be brought in direct contact with the gear wheel 35 and thus the drum gear wheel 21 and the drum itself will be driven in one direction.
- 10 When the lever is shifted toward the left in Figure 4 the intermediate gear wheel 34 will mesh with the gear wheel 36 and, therefore, a reverse rotation will be transmitted to the drum gear wheel 21 and drum.
- 15 In order to secure the automatic reversal of the direction of rotation of the drum, it is necessary to shift the lever 32 automatically in opposite directions. To this end, I mount upon the outer face of the cross bar 20 25 a transversely shiftable rod 38, one-half of which is screw-threaded, as at 39. The toothed nut 29 before referred to is, of course, internally screw-threaded to engage with the screw-threaded portion 39 and this 25 nut is held from any longitudinal movement by means of the bearings 40 which are attached to the cross bar 25.
- It will be obvious now that as the gear 30 wheel 21 revolves, rotation in one direction will be communicated to the pinion 28 which will rotate the nut 29 and that this acting upon the screw-threads 39 will shift the slide bar 38 transversely of the machine and transversely to the lever 32. Attached to 35 the ends of this slide rod 38 and moving therewith but disposed above and in parallel relation to the bar 38 is a bar or rod 41 which is formed at separated points with the upwardly extending shoulders 42 having inclined faces 43. The lever 32 is deflected so as to extend outward of the outside face of the bar 41 and outward of the rod 38, and this lever carries upon it a vertically disposed bolt 44 urged downward by a 40 spring 45, which bolt at its lower end is adapted to engage in notches 46 formed in a cross bar 47 mounted upon the frame and disposed outward of the cross bar 25. When 45 this latch bolt 44 is raised against the action of the spring 45, it will be withdrawn from the notches 46, but when depressed into one or the other of the notches it will hold the lever to one side or the other of its neutral position and, therefore, the lever will be 50 held in such position that the gears 33 and 34 will drive either the gear wheel 35 or the gear wheel 36.
- Attached to the upper end of the lever on the rear face thereof is a coiled contractile 55 spring 48. This spring passes through an opening in the middle of the rod 38 and this spring is connected at its lower end to the lower middle portion of the lever 32. It, therefore, follows that when the lever is 60 shifted in one direction as, for instance, to-

ward the left in Figure 4 and the bolt or latch 44 is engaged in the left hand notch 46 that as the nut 29 shifts the rod to the right, the middle portion of the spring will be also pulled to the right, thus exerting a tension on the spring. As the bar 41 moves toward the right in Figure 5 the left hand shoulder or cam portion 43 coming in contact with the projection on the latch 44 will raise it against the action of the spring 45 and the minute the latch is raised out of the notch 46, the spring 48 will pull the lever quickly over until the latch 44 again engages in one of the notches 46. As soon as this has been done, the gear wheels 33 and 34 will be shifted by the lower end of the lever so as to reverse the motion of the drum and of the gear wheel 21 and, as this reverses, the motion of the nut will be reversed so that the rod 38 will travel in a reverse direction and will repeat the action just described, releasing the latch and causing the spring to again pull the lever reversely, which will, of course, reverse the motion of the drum.

The driving gears are of such proportion 90 and the screw-threads 39 on the rod 38 are of such pitch that the drum will rotate in one direction thirty-three times a minute and then reversely rotate thirty-three times in the opposite direction for the next minute 95 and so on until the lever 32 is shifted by hand to a neutral position. In this neutral position it is held by a hasp 49 which travels over the bar 47, this bar 47 being provided with an aperture 50 and the hasp having an 100 aperture through which a pin 51 on a chain 52 may be inserted, thus locking the lever 32 in its neutral position with any of the gears 33 or 34 engaging the respective gears 35 and 36, whereupon the washing machine will 105 come to a stop.

Preferably the gearing heretofore described is disposed within an outer frame 53 which is operatively connected at the narrow portion 54 to the upright members 37, 110 this frame including a lower transverse bar 55 having inwardly projecting bolts 56 whereby the gear supporting frame may be engaged with the washing machine itself. The cross bar 25 is also provided with inwardly projecting bolts 57 engageable with the frame of the washing machine. This outer frame is held in spaced relation to the washing machine by an inner frame 58 braced from the outer frame at intervals. 115

Extending over the space defined by the cross bar 25 and by the outer supporting bars 37 on the frame is a panel 59 comprising a marginal frame 60 and wire netting 61, and wire netting 62 is applied between the upright members 37 and the frame 53 and between the upper portion of the frame 53 and the cross bar 25 so that all of the gearing except the reciprocating rod 38, the reciprocating bar 41 and the upper portion of 125 130

the lever are enclosed or protected by this wire netting. The upper end of the lever is angularly bent at 63 so that the handle of the lever extends vertically upward just 5 above the upper portion of the gear supporting frame.

As described in my prior patent, there is mounted upon the supporting frame of the washing machine a blower, designated generally 64, having therein a fan 65. This blower extends upward and at its upper end opens into the interior of the outer casing and the discharge of air from the blower into the outer casing is controlled by the 10 valve 66. Within the blower casing there is disposed the rotatable fan 65, as previously stated, which is mounted upon a shaft 67. This shaft carries upon it a pinion 68.

Mounted upon the shaft 30 is a gear wheel 20 69 which is thus adapted to be rotated by the motor and meshing at all times with this gear 69 is a gear wheel 70 carried by a lever 71, this lever extending upwardly and laterally through an opening in the gear housing 25 or gear case and being provided with a hand operated latch 72 of ordinary form whereby the lever may be locked in either of two positions, this latch operating upon a vertical portion of the frame, designated 73, having 30 notches 74 for the reception of the latch. When the lever is in one position, the gear wheel 70 will be out of mesh with the pinion 68. When the gear wheel is moved in the other direction, however, it will be in mesh 35 with the pinion 68 and power will be transmitted to the fan of the blower. It will be understood that this blower is not to be operated when the tank has water in it, but when the tank has no water in it or the 40 water has been let out through the drain pipe 75, then the blower may be operated to blow a blast of air into the tank and this, as the drum is rotated, will cause the clothes to be dried off. Of course, the valve 66 may be 45 used to control this jet of air or to cut it off entirely.

The operation of the mechanism has been heretofore described in detail so it is not believed necessary to reiterate it, except to 50 state in a general way that after the clothes have been placed within the oscillatable clothes holder the lever 32 is shifted from a neutral position into one of its inclined positions, and this starts the machine by 55 throwing the gears carried by the lever into engagement with one or the other of the gear wheels 35 or 36. Thereafter the relation is automatic in its character and reverses after any predetermined number of revolutions. The clothes are, therefore, constantly 60 tumbled about in the water which fills the interior of the drum or clothes holder and this, of course, acts to cleanse the clothes. The rotation of the clothes in one direction followed by a plurality of reverse rotations 65

causes a most thorough agitation and cleansing of the clothes. After the clothes have been cleansed, the lever is shifted to its neutral position, the water drawn off, and then the air from the blower may be blown into 70 the interior of the washing machine to dry the clothes.

While I have illustrated certain details of construction and arrangement of parts which have been found to be particularly effective in actual practice, I do not wish to be limited to this as obviously these details might be changed without departing from the spirit of the invention as defined in the appended claims. Preferably, though 75 not necessarily, the gearing for driving the drum and the blower with the casing in which the gearing is mounted is removable 80 as a unit from the side of the washing machine. 85

I claim:—

1. Driving mechanism for washing machines comprising a driven shaft and means for oscillating the driven shaft in opposite directions comprising gear wheels operatively connected to the driven shaft to rotate it, a drive shaft, a driving gear thereon, a shiftable lever and a gear carried thereby meshing with the driving gear, an intermediate pinion carried by the lever and meshing with the gear on the lever, the lever when shifted in one direction carrying the intermediate pinion into engagement with one of the first named gear wheels and when shifted in the other direction carrying the gear on the lever into engagement with the other of said first named gear wheels, means operating automatically after a predetermined number of rotations of the driven shaft causing the lever to shift from one 105 position to its other position including a gear wheel connected to and rotating with the driven shaft, a transversely extending rod having screw-threads, a toothed nut on said screw-threads held from longitudinal 110 movement connected to and operated by the gear wheel on the driven shaft, resilient means carried by said screw-threaded rod and yieldingly engaging the lever and acting to urge the lever in the direction of movement of the rod, means for latching the lever in either of its shifted positions, and means reciprocating with the screw-threaded rod acting to release said latching means when the screw-threaded rod has moved a predetermined amount. 115

2. In a driving mechanism of the character described a driven shaft and means for oscillating the driven shaft in opposite directions comprising gear wheels operatively connected to the driven shaft to rotate it, a drive shaft, a driving gear thereon, a shiftable lever and a gear carried thereby meshing with the driving gear, an intermediate pinion carried by the lever and meshing 120 125 130

with the gear on the lever, the lever when shifted in one direction carrying the intermediate pinion into engagement with one of the first named gear wheels and when shifted in the other direction carrying the gear on the lever into engagement with the other of said first named gear wheels, means operating automatically after a predetermined number of rotations of the driven shaft causing the lever to shift from one position to its other position including a gear wheel connected to and rotating with the driven shaft, a transversely extending rod having screw-threads, a toothed nut on said screw-threads held from longitudinal movement connected to and operated by the gear wheel on the driven shaft, a resilient means carried by said screw-threaded rod and yieldingly engaging the lever and acting to urge the lever in the direction of movement of the rod, means for latching the lever in either of its shifted positions, a bar carried by and movable with the screw-threaded rod and having shoulders formed with inclined faces, the shoulders acting alternately to release the latching means of said lever and thereby permit the lever to shift to its other position upon each complete reciprocation of the screw-threaded rod.

3. In driving mechanism of the character described a driven shaft, a gear wheel mounted upon the shaft, means for intermittently reversing the direction of movement of the gear wheel including a pair of gear wheels having operative connection with the gear wheel on the driven shaft, a driving gear wheel, a lever pivoted upon the axis of the driving gear wheel, a gear wheel carried by the lever and meshing with the driving gear wheel and adapted when the lever is thrown in one direction to engage with one of said pair of gear wheels, a pinion mounted upon said lever and meshing with the gear wheel mounted thereon and adapted when the lever is thrown in the other direction to mesh with the other of said pair of gear wheels, means for intermittently shifting said lever including a transversely extending rod slidably mounted in bearings, one portion of the rod being screw-threaded, a toothed nut engaging the screw-threaded rod and held from lateral movement, means for rotating said toothed nut from the gear wheel on the driven shaft, a spring connected at its middle to said rod and at its ends to the lever, said spring acting as the rod is shifted in one or the other direction to urge the lever in the direction of pull of the spring, a latch carried by the lever, a cross bar having notches with which the latch is adapted to engage to hold the lever in either of two adjusted positions and thereby hold the gear wheel and pinion carried by the lever in engagement with one or the other of the first named pair of gear wheels, means for releasing said latch comprising a transversely extending bar carried by the threaded rod and having spaced shoulders formed with inclined faces adapted to alternately engage and lift the latch.

4. In driving mechanism of the character described, a driven shaft, a gear wheel mounted upon the driven shaft, means for intermittently reversing the direction of movement of the gear wheel including a pair of gear wheels having operative connection with the gear wheel on the driven shaft, a driving gear wheel, a lever pivoted upon the axis of the driving gear wheel, a gear wheel carried by the lever and meshing with the driving gear wheel and adapted when the lever is thrown in one direction to engage with one of said pair of gear wheels, a pinion mounted upon said lever and meshing with the gear wheel mounted thereon and adapted when the lever is thrown in the other direction to mesh with the other of said pair of gear wheels, means for intermittently shifting said lever including a transversely extending rod slidably mounted in bearings, one portion of the rod being screw-threaded, a toothed nut engaging the screw-threaded rod and held from lateral movement, means for rotating said toothed nut from the gear wheel on the driven shaft, a spring connected at its middle to said rod and at its ends to the lever, said spring acting as the rod is shifted in one or the other direction to urge the lever in the direction of pull of the spring, a latch carried by the lever, a cross bar having notches with which the latch is adapted to engage to hold the lever in either of two adjusted positions and thereby hold the gear wheel and pinion carried by the lever in engagement with one or the other of the first named pair of gear wheels, means for releasing said latch comprising a transversely extending bar carried by the threaded rod and having spaced shoulders formed with inclined faces adapted to alternately engage and lift the latch, and means for locking the lever in a neutral position.

5. In a gearing of the character described, a rotatable element, a pair of driving gears operatively engaged therewith, a driving gear wheel and a pinion geared thereto alternately engageable with the driving gears, respectively, means for driving the driving gear wheel, a lever supporting the driving gear wheel and pinion and adapted when shifted in one direction to carry the driving gear wheel into engagement with one of said driving gears and when shifted in the other direction to carry the pinion into engagement with the other of said driving gears, and means for automatically shifting said lever comprising a rack with which the lever coacts having two locking notches adapted to hold the lever either in one of its

and means for releasing said latch comprising a transversely extending bar carried by the threaded rod and having spaced shoulders formed with inclined faces adapted to alternately engage and lift the latch.

70

4. In driving mechanism of the character described, a driven shaft, a gear wheel mounted upon the driven shaft, means for intermittently reversing the direction of movement of the gear wheel including a pair of gear wheels having operative connection with the gear wheel on the driven shaft, a driving gear wheel, a lever pivoted upon the axis of the driving gear wheel, a gear wheel carried by the lever and meshing with the driving gear wheel and adapted when the lever is thrown in one direction to engage with one of said pair of gear wheels, a pinion mounted upon said lever and meshing with the gear wheel mounted thereon and adapted when the lever is thrown in the other direction to mesh with the other of said pair of gear wheels, means for intermittently shifting said lever including a transversely extending rod slidably mounted in bearings, one portion of the rod being screw-threaded, a toothed nut engaging the screw-threaded rod and held from lateral movement, means for rotating said toothed nut from the gear wheel on the driven shaft, a spring connected at its middle to said rod and at its ends to the lever, said spring acting as the rod is shifted in one or the other direction to urge the lever in the direction of pull of the spring, a latch carried by the lever, a cross bar having notches with which the latch is adapted to engage to hold the lever in either of two adjusted positions and thereby hold the gear wheel and pinion carried by the lever in engagement with one or the other of the first named pair of gear wheels, means for releasing said latch comprising a transversely extending bar carried by the threaded rod and having spaced shoulders formed with inclined faces adapted to alternately engage and lift the latch, and means for locking the lever in a neutral position.

100

5. In a gearing of the character described, a rotatable element, a pair of driving gears operatively engaged therewith, a driving gear wheel and a pinion geared thereto alternately engageable with the driving gears, respectively, means for driving the driving gear wheel, a lever supporting the driving gear wheel and pinion and adapted when shifted in one direction to carry the driving gear wheel into engagement with one of said driving gears and when shifted in the other direction to carry the pinion into engagement with the other of said driving gears, and means for automatically shifting said lever comprising a rack with which the lever coacts having two locking notches adapted to hold the lever either in one of its

110

115

120

125

130

- positions or in the other of its positions, a bolt on the lever adapted to engage said notches, an element shiftable parallel to the movement of the lever having two cam portions thereon adapted to alternately engage the bolt and lift it from one or the other of the notches, means for operatively connecting the shiftable element to the rotatable element whereby to shift the shiftable element 5 as the rotatable element rotates, and means carried by the shiftable element and connected to the lever exerting tension on the lever and acting to shift the lever suddenly from one of its two positions to the other of 10 its positions.
6. In a gearing of the character described, a rotatable element, a pair of driving gears operatively engaged therewith, a driving gear wheel and a pinion geared thereto alter- 20 nately engageable with the driving gears, respectively, means for driving the driving gear wheel, a lever supporting the driving gear wheel and pinion and adapted when shifted in one direction to carry the driving gear 25 wheel into engagement with one of said driving gears and when shifted in the other
- direction to carry the pinion into engage-
ment with the other of said driving gears,
and means for automatically shifting said
lever comprising a rack with which the lever 30
coacts having two locking notches adapted
to hold the lever either in one of its pos-
itions or in the other of its positions, a bolt
on the lever adapted to engage said notches,
an element shiftable parallel to the move- 35
ment of the lever having two cam portions
thereon adapted to alternately engage the
bolt and lift it from one or the other of the
notches, means for operatively connecting
the shiftable element to the rotatable ele- 40
ment whereby to shift the shiftable element
as the rotatable element rotates, and a spring
connected to said lever and to the shiftable
element and placed under tension when the
shiftable element shifts away from the lever 45
and acting, when the bolt is released, to
shift the lever suddenly from one of its
operative positions to the other of its op-
erative positions.

In testimony whereof I hereunto affix my 50
signature.

FRANK WILSON.
